UNITED STATES PATENT OFFICE.

JEREMIAH J. O'CONNOR AND JOHN A. O'CONNOR, OF PAWTUCKET, ASSIGNEES
OF ONE-THIRD TO ALBERT H. ALLEN, OF PROVIDENCE, RHODE ISLAND.

MACHINE FOR TWISTING THREAD, &c.

SPECIFICATION forming part of Letters Patent No. 354,926, dated December 28, 1886.

Application filed July 24, 1885. Serial No. 172,586. (No model.)

To all whom it may concern:

Be it known that we, JEREMIAH J. O'CONNOR and JOHN A. O'CONNOR, both of Pawtucket, in the county of Providence and State of Rhode Island, have jointly invented a new and useful Improvement in Machines for Twisting Thread and other Yarns; and we do hereby declare the following specification, taken in connection with the accompanying drawings, to forming a part of the same, to be a description thereof.

This invention relates to machines for twisting thread or other yarns; and it consists in combining with such a machine a device for cutting or severing the thread or yarn between the delivery bobbins or spools and the top rolls of the machine when by accident the thread or yarn becomes broken between the said top rolls and the receiving bobbins or spools, and thereby preventing the thread or yarn being delivered from running to waste, as will be hereinafter described, and set forth in the claims.

For illustrating the invention we have chosen a well-known thread-twisting machine.

In the accompanying drawings, Figure 1 shows a front view of a portion of such a machine with our improved device for cutting or severing the thread applied thereto. Fig. 2 shows a top view of the same. Fig. 3 represents a vertical section of the same on line *xx* of Fig. 1. Fig. 4 shows in perspective certain parts of the machine and our device combined therewith.

A is the frame of the machine.

B are the delivery bobbins or spools, and B' the creel or stand, upon pegs, *b*, projecting from which the bobbins B are mounted.

C are the receiving-bobbins mounted upon the spindles D, which spindles are driven, in the usual manner, by bands *d*, Fig. 3, from the spindle-drum E.

F is the ring-rail, which is furnished with the rings *f* and their travelers.

G is the bottom roll, which is driven from the drum E by a suitable and well-known train of gears, *e*, *e'*, *e''*, *e'*, and *e*', Fig. 1, the gear *e* being secured to the drum-shaft, and the gear *e*' to the shaft *g* of the roll G.

H are the top rolls, which are loosely mounted

to revolve in bearings H', Figs. 1 and 2, by frictional contact with the roll G, or with the threads passing between said rolls.

J is the guide-board over which the threads *a* pass from the bottom roll, G, to the receiving-bobbins C.

K is a bar having guide-eyes *k* for receiving the threads from the delivery-bobbins B.

L is a trough for holding water to wet the thread and thereby facilitate the twisting operation, and *l* is a glass guide-rod for keeping the threads submerged as they pass through the water-trough L. The course of each thread *a* is from its bobbin B through the guide-eyes *k*, *k*', thence under the rod *l* and over and partially around the roll H, thence partially around the roll G to the guide-board J, and from thence to a ring-traveler and a receiving-bobbin C. As above described, the machine is of the usual construction.

Our device for cutting or severing the thread between the delivery-bobbins and the feed-rolls will now be described, it being understood that as many of these devices are employed as there are threads running to the feed-rolls G H.

M is a bell-crank lever, which is pivoted at its angle to one end of a lever, N, mounted to tilt or swing vertically on a standard, *n*, secured to the frame of the machine, as particularly shown in Figs. 3 and 4. The free end *m* of the horizontal arm of the lever M is in the form of an eye or hook, which engages and is supported by the thread while the latter is passing taut from the bottom roll, G, to the receiving-bobbin C. The free end *m'* of the vertical arm of the lever M is bent at right angles, or furnished with a tooth to engage, when allowed to do so, with one of the studs *h*, which may be more or less in number, projecting from the side of a roll, H, in close proximity to which the end or tooth *m'* of the lever M is normally located.

To the rear or inner end of the lever N a two-part link, O, is pivoted, which link forks the head of a knife, P, forming one member of a shear, the other member, P', of which consists of a block having a slot, *p*, in which the member or knife P' is arranged to move vertically. The shear member P' is furnished with oppositely-located holes, one, *p'*, of which is shown

in Fig. 4, and through these holes the thread *a* passes, under the knife *P*, on its way from the eye *k* to the eye *k'*.

The operation of the device is as follows:

- 5 During the normal running of the machine the thread *a* is taut between the roll *G* and the guide-board *J*, being held in such condition by the twisting operation, and the bent end or tooth *m'* of the lever *M* is held out of the path 10 of movement of the studs *h* on the roll *H* by the engagement of the eye *m* with such taut thread. When, however, the thread breaks between the rolls *G* *H* and the receiving-bobbin *C* the eye *m* of the lever *M* will no longer 15 be supported in the position shown in Figs. 2 and 4, and the lever *M* will tilt under the influence of the weight of its horizontal arm and cause the bent end *m'* of its vertical arm to swing into the path of movement of the revolving studs *h*, by one of which the said end or tooth *m'* will be engaged as the roll *H* revolves in the direction of the arrow. The engagement of a stud, *h*, with the end or tooth *m'* of the lever *M* will raise said lever, thereby 20 tilting the lever *N* and moving the knife *P* downwardly, and causing the shear *P* *P'* to cut or sever the thread. The thread being cut, no more will pass from the delivery-bobbin *B*, and only that amount of thread between the break 25 and the cut will be wasted.

In the machine shown in the drawings the thread upon a bobbin, *B*, consists of two strands, both of which are drawn from said bobbin and pass through the same eye, *k*, and thence between the bottom roll, *G*, and a top roll, *H*, to be twisted. As will be readily understood, our improvement is equally applicable when the threads from two or more bobbins are together drawn through the same 30 guide-eye, *k*, to make a thread or yarn of larger size or greater weight.

If desired, the guide-eyes *k* *k'* may be dispensed with, and the holes in the shear member *P'* be allowed to act as guides for the thread passing from the delivery-bobbins, as will be readily understood.

When it is considered that, in a machine as ordinarily constructed without our improvement, thread will be drawn from the delivery-bobbin and will run to waste, (if the thread breaks between the top and bottom rolls and the receiving-bobbin,) until the attention of the operative is called to the matter, it will readily be seen that a great saving in thread 40 or yarn will be effected by the use of our device, which is automatic in its operation.

What we claim as our invention, and desire to secure by Letters Patent, is—

1. The combination, with the top and bottom rolls and the spindles, of a shear having 60 a movable member and mechanism, substantially as described, connecting the movable member with the rolls, whereby the movable member is operated by the rolls for severing the thread or yarn before it reaches said rolls 65 when the thread or yarn breaks between said rolls and spindles, substantially as and for the purpose described.

2. The combination, with the top and bottom rolls, the former of which is provided with 70 studs, and the spindle, of a shear having a movable member and mechanism, substantially as described, connected with the movable shear member and operated by the studs on said upper roll, substantially as and for the 75 purpose set forth.

3. The combination, substantially as herein set forth, with the top and bottom rolls, the former of which is provided with a stud or studs, and the spindles, of a pivoted lever, *M*, 80 provided with an eye or hook, *m*, and a projection or tooth, *m'*, the said tooth being normally held out of the path of movement of said spur or spurs, as described, a shear through which the thread or yarn passes to said rolls, 85 and connections, substantially as described, between the said lever and shear for communicating motion to the shear when the tooth *m'* is engaged by the said spur or spurs.

4. The combination, with the top and bottom rolls, the former of which is provided with a stud or studs, and the spindles, of the lever *M*, having an eye or loop, *m*, and tooth *m'*, the lever *N*, to which lever *M* is pivoted, a suitable pivot or support for the lever *N*, the 90 movable shear member *P*, connected to the lever *N*, the shear member *P'*, the said shear having a passage for the thread, and a support for the shear member *P'*, substantially as and for the purpose specified. 100

5. The thread or yarn severer herein described, consisting of the lever *M*, having a loop or eye, *m*, and tooth *m'*, the lever *N*, to which lever *M* is pivoted, the shear member *P*, 105 connected to the lever *N*, and the shear member *P'*, the said shear having a passage for the thread or yarn, the whole being adapted to be attached to a machine for twisting thread or yarn, substantially as and for the purposes specified.
